OTIS C. FUNDERBURK, OF DETROIT, MICHIGAN, ASSIGNEE TO DETROIT LUBRICATOR COMPANY, OF DETROIT, MICHIGAN, A CORPORATION OF MICHIGAN.

CARETAKER.

1,159,005.

Specification of Letters Patent. Patented Nov. 2, 1915.

Application filed May 11, 1914. Serial No. 887,831.

To all whom it may concern.

Be it known that I, OTIS C. FUNDERBURK, a citizen of the United States of America, residing at Detroit, in the county of Wayne 5 and State of Michigan, have invented certain new and useful Improvements in Carbureters, of which the following is a specification, reference being had thereto to the accompanying drawing.

10 The invention relates to carbureters of the type in which a variable flow of the liquid fuel is automatically obtained by the relative adjustment of a metering pin forming a restriction in the oil conduit, this adjustment 15 in turn being effected by the movement of the auxiliary air valve, due to variable suction. With constructions of this type a gradual opening of the throttle will produce a proportionate increase in the volume of 20 air and oil, but where there is a sudden opening of the throttle there is frequently a failure in response. Furthermore, there is a tendency for the auxiliary air valve to jump to the extreme open position and then to 25 instantaneously close before the column of oil has had time to change its rate of flow.

It is the object of the present invention to avoid this difficulty, first, by preventing the abnormal opening of the auxiliary air valve, 30 and further by more rapidly accelerating the flow of the oil and maintaining the increased flow for a longer period of time.

The invention therefore comprises various features of construction as hereinafter set 35 forth.

In the drawings: Figure 1 is a vertical central section through the carbureter; Fig. 2 is a similar view showing the parts in a different position of adjustment.

40 A is the casing containing a mixing chamber B, preferably of a pear-shaped form, and having a throttle valve C at its upper end, which as shown is of the butterfly type.

D is the float chamber having a conduit E 45 leading to a cylindrical chamber F in which is arranged a hollow piston G having a central oil discharge nozzle H and a surrounding auxiliary air valve I. The valve I is normally seated to close direct communication 50 between the mixing chamber B and the air chamber J beneath the same, which latter has an open atmospheric connection. Said valve has a central opening I', communicating with the mixing chamber B, and 55 the upper or discharge end of the nozzle H

terminates within said opening I'. Primary air passages J' are formed in the valve I to establish communication between the opening I' and the air chamber J.

K is a tapering metering pin which is arranged in the lower end of the nozzle H and is adjustable to variably restrict the inlet into said nozzle for the oil. This pin is provided with an adjusting mechanism, preferably comprising a head L at the lower end 60 of the pin slidably engaging a cylindrical guide M. L' is an adjustable head above the head L having annular rack teeth in its periphery, which are in mesh with a pinion N upon a rock-shaft N' extending out from 65 the casing. N² is a rock-arm on the rock-shaft N', carrying at its outer end an adjustable screw N³ for engaging a stop-plug N⁴, the arrangement being such that by adjusting said screw the position of the rock-arm N² and rock-shaft N' may be varied, 70 which will correspondingly vary the position of the pinion N, heads L' and L and metering pin K.

In addition to the manual adjustment of 80 the metering pin by the mechanism just described, there is an automatic adjustment effected by the movement of the air valve I and piston G. This is due to the fact that the nozzle H is mounted upon and carried by 85 the piston G and consequently whenever said piston is lifted by the upward movement of the air valve, due to increased suction, there will be a corresponding lifting of the nozzle which adjusts it relatively to the metering 90 pin. This automatic adjustment has been provided in carbureters of the type heretofore constructed, but as has been stated, the results have not been satisfactory, due to the greater inertia of the oil. I have therefore 95 provided additional means for more instantaneously adjusting the metering pin, constructed as follows: O is a passage connecting with the lower end of the cylinder F and leading to the lower end of the cylinder M 100 beneath the slidible head L. P is a spring for normally holding the head L against the adjacent head L'. Q is an upwardly-opening check valve in the passage O. The construction just described is such that when 105 the piston G is lifted by the upward movement of the valve I, a vacuum will be produced in the lower end of the cylinder F, which will be communicated through the passage O to the lower end of the cylinder 110 H.

M, causing the head L to be drawn downward against the tension of the spring P at the same time that the nozzle H is moving upward with the piston G. This will produce a sudden increase in the area of opening into the nozzle H through which the oil is permitted to pass, which will cause a corresponding increase in the amount discharged into the mixing chamber. When the metering pin is thus adjusted the closing of the check valve Q will prevent the instantaneous return of said pin, even where the air valve is permitted to drop, but the gradual leakage of oil around the heads L and L' will permit the slow return movement of the metering pin under the actuating pressure of the spring P. Thus it is apparent that the cylinder F and piston G coöperate to form a dash-pot acting to resist any sudden opening of the valve I, and it is further apparent that the suction of said dash-pot, when the piston G is suddenly raised, will act to increase the flow of liquid fuel.

In the operation of the carbureter whenever the throttle valve C is quickly thrown open the lowering of pressure in the mixing chamber B will cause the rise of the valve I by the atmospheric pressure of air in the chamber J. There is not, however, the same tendency for the valve I to jump to its extreme position, as with the case of constructions of this type heretofore used. This is probably due to the fact that the head L is freely movable and is resisted only by the tension of the comparatively light spring P, so that the oil beneath this head is displaced to compensate for the displacement of the piston G. Thus there is not the same initial resistance to the movement of the piston G, and this prevents the extreme differential pressure upon the air valve I which would occur if that valve were held temporarily upon its seat. In other words, with the constructions previously used the temporary holding of the air valve to its seat causes a much higher vacuum in the mixing chamber, with a result that when the valve does move it acquires a high velocity which shoots it beyond the point at which the air pressures balance.

The opening of the air valve I causes the displacement of the piston G and the resulting lowering of the head L carrying the metering pin K, which, by increasing the entrance orifice for the oil in the nozzle H, permits of a corresponding increase in the discharge in the mixing chamber. The check valve Q is lifted during the downward movement of the head L so that the oil there beneath may be displaced into the cylinder F, but the instantaneous closing of said check valve will prevent the return movement so that the metering pin remains in lowered position. Thus the increased flow of oil through the nozzle continues for a period of

time determined by the pressure of the spring P and the leakage of oil about the heads L and L', and this may be made sufficiently long to insure a proper proportion of oil with the air during a quick pick up.

When the throttle valve C is opened or closed, gradually the leakage of the oil about the piston G and the heads L and L' will prevent the downward displacement of the metering pin, but the upward movement of the piston G will effect a relative movement of the nozzle H and the metering pin to increase the flow of oil.

What I claim as my invention is;

1. In a carbureter, the combination with a casing containing the mixing chamber, of a valve controlling the air inlet to said chamber, a nozzle for discharging oil into said chamber, means controlled by the movement of the air inlet valve for varying the discharge of oil, and means operating upon the sudden opening of said air valve for maintaining a temporary increase in the discharge of the oil independent of the position of said air valve subsequent to its sudden movement.

2. In a carbureter, the combination with the casing containing the mixing chamber, of a valve controlling the air inlet to said chamber, a nozzle for discharging oil into said chamber, means operated by the normal movement of said air valve for proportionately varying the discharge of oil, and means operated by the sudden movement of said air valve for additionally increasing the discharge of oil and temporarily continuing said increased discharge.

3. In a carbureter, the combination with a casing and mixing chamber, of a valve controlling the air inlet into said chamber, a nozzle for discharging oil into said chamber, means operated by the normal movement of said air valve for proportionately varying the discharge of oil, and means operated by a sudden opening of said air valve for abnormally increasing the discharge of oil and gradually diminishing said discharge to the normal rate.

4. In a carbureter, the combination with a casing having a mixing chamber, of a valve controlling the air inlet into said chamber, a nozzle for discharging oil into said chamber, a metering pin for varying the discharge of oil automatically adjusted by the movement of said air valve, and means operating upon a sudden opening of said air valve for abnormally adjusting said metering pin to increase and temporarily maintain an increased discharge of oil.

5. In a carbureter, the combination with a casing containing a mixing chamber, a nozzle for discharging oil into said chamber, a valve controlling the air inlet into said chamber, a metering pin controlling the oil discharge from said nozzle, means operated by

the normal movement of said air valve for varying the relative position of said metering pin, and means operating upon the sudden movement of said air valve for abnor-
5 mally adjusting said metering pin and temporarily maintaining said adjustment.

6. In a carbureter, the combination with a casing containing the mixing chamber, of an automatic valve controlling the air inlet
10 to said chamber, a nozzle for discharging the liquid fuel into said chamber, a dash pot for resisting the sudden opening of said air inlet valve, and means operated by the suction of said dash pot for increasing the flow
15 of liquid fuel.

7. In a carbureter, the combination with a casing containing the mixing chamber, of an automatic valve controlling the air inlet to said chamber, a nozzle for discharging
20 liquid fuel into said chamber, a dash pot for resisting the sudden opening of said automatic valve, a metering pin for variably restricting the flow of liquid fuel to said nozzle, and means operated by the suction
25 of said dash pot for adjusting said metering pin to increase the flow of liquid fuel.

8. In a carbureter, the combination with a casing containing the mixing chamber, of an automatic valve controlling the air inlet
30 to said chamber, a nozzle for discharging the liquid fuel into said chamber, a dash pot for resisting the sudden opening of said automatic valve, a metering pin for variably restricting the flow of liquid fuel to said nozzle in different positions of adjustment of
35 said automatic valve, means operated by the suction of said dash-pot for adjusting said metering pin to further increase the flow of liquid fuel, and means for restoring said
40 metering pin to normal position upon the cessation of the suction of said dash-pot.

9. In a carbureter, the combination with a casing containing the mixing chamber, of an automatic valve controlling the air inlet
45 to said chamber, a nozzle for discharging the liquid fuel into said chamber, a piston connected to said automatic valve, a cylinder in which said piston is arranged coöperating therewith to form a dash-pot for resisting

the sudden opening of said valve, a meter- 50 ing pin, a piston in which said metering pin is mounted, a cylinder for said piston connected with the cylinder of said dash pot, whereby the metering pin is shifted by the suction of the dash pot, and means coöper- 55 ating with said metering pin for variably restricting the flow of liquid fuel with each position of adjustment of said automatic valve and for further increasing the flow upon the actuation of said metering pin by 60 the suction of said dash pot.

10. In a carbureter, the combination with a casing containing a mixing chamber, of a nozzle for discharging oil into said chamber, a metering pin limiting the fuel supply 65 to the nozzle, and means operating upon an increase in the velocity of air passing through said chamber for simultaneously displacing the nozzle and metering pin op- 70 positely.

11. In a carbureter, the combination with a casing containing a mixing chamber, of a nozzle for discharging oil into said chamber, a metering pin limiting the supply of oil to the nozzle, means for manually adjusting 75 the metering pin relative to the nozzle, and means operating upon a change in the velocity of air passing through the mixing chamber for displacing the metering pin to vary the fuel supply. 80

12. In a carbureter, the combination with a casing containing a mixing chamber, of a nozzle for discharging oil into said chamber, means for normally proportioning the supply of fuel to the velocity of air passing 85 through the mixing chamber, and means operating upon a sudden increase in the velocity of air passing through the mixing chamber for abnormally increasing the discharge of oil and gradually diminishing said dis- 90 charge to the normal rate.

In testimony whereof I affix my signature in presence of two witnesses.
